UNITED STATES PATENT OFFICE.

SETH WILLIAM BABBITT, OF MERIDEN, CONNECTICUT, ASSIGNOR TO THE INTERNATIONAL SILVER COMPANY, OF MERIDEN, CONNECTICUT.

DESIGN FOR A BRANCH ARM FOR SOLID OR PLATED METAL WARE.

SPÉCIFICATION forming part of Design No. 35,241, dated October 29, 1901.

Application filed September 24, 1901. Serial No. 76,407. Term of patent 7 years.

To all whom it may concern:

Be it known that I, SETH WILLIAM BABBITT, a citizen of the United States, residing at Meriden, in the county of New Haven and State of Connecticut, have invented and produced a new and original Design for Branch Arms for Solid or Plated Metal Ware; and I do hereby declare the following to be a full, clear, and exact description of the same, reference being had to the accompanying drawing, forming a part thereof.

This invention relates to a new and original design for branch arms for solid and plated metal ware; and it is embodied in the general formation and configuration shown in the accompanying drawing, hereinafter described.

In the drawing the design is illustrated in perspective.

The general features of the design reside in two curved members A B, their adjacent ends being fancifully formed and united with the fanciful portion of the arm B, extended upward, and the fanciful portion of the arm A extended downward. The arm A is curved

throughout its length, and at its opposite end 25 it is curved transversely, as at a, and terminates in a drop or depending portion a'. The arm B is substantially of U-shaped formation, somewhat irregular in its curvature, and its outer end is projected upwardly and carries an ornamental finishing-cap C.

The essential features of the design as described and represented reside in the peculiar arrangement of the adjacent ends of the two members or portions and the peculiar curvatures of the two members of the arm.

Having thus described the invention, what is claimed as new, and desired to be secured by Letters Patent, is—

The design for a branch arm for solid and plated metal ware substantially as shown and described.

In testimony whereof I affix my signature in presence of two witnesses.

SETH WILLIAM BABBITT.
